DESIGN FOR AN ASH TRAY

Wallace A. Davidson, South San Francisco, Calif.

Application September 11, 1944, Serial No. 115,267

Term of patent 7 years

(Cl. D85—2)

To all whom it may concern:

Be it known that I, Wallace A. Davidson, a citizen of the United States of America and a resident of the city of South San Francisco, county of San Mateo, and State of California, have invented a new, original, and ornamental Design for an Ash Tray, of which the following is a specification, reference being had to the accompanying drawing, forming part of this application, in which:

Figure 1 is a perspective view of an ash tray showing my new design;

Figure 2, a top plan view of the same; and

Figure 3, a vertical section through the same taken along line 3—3 of Figure 2.

I claim:

The ornamental design for an ash tray, substantially as shown.

WALLACE A. DAVIDSON.
